UNITED STATES PATENT OFFICE.

THEODORE BUTLER, OF DETROIT, MICHIGAN.

SHOE-FASTENER.

1,276,026.

Specification of Letters Patent. Patented Aug. 20, 1918.

Application filed April 6, 1918. Serial No. 227,075.

To all whom it may concern:

Be it known that I, THEODORE BUTLER, a citizen of the United States, residing at Detroit, in the county of Wayne and State 5 of Michigan, have invented certain new and useful Improvements in Shoe-Fasteners, of which the following is a specification.

This invention relates generally to shoe fasteners, aiming primarily to provide 10 proved means for use upon shoes to obviate the necessity of laces and buttons now used for holding the shoes upon the feet, which will insure proper fitting of the shoes, which will hold the upper snugly upon the foot, 15 and which will present an attractive appearance.

A further object of the invention is to provide a shoe fastener which may be quickly and easily applied to or removed from the 20 shoe, and which is constructed in such manner as to adapt itself to the configuration of the instep.

With these objects in view, together with others which will appear as the description 25 proceeds, the invention resides in the novel formation, combination and arrangement of parts, all as will be described more fully hereinafter, illustrated in the drawings, and particularly pointed out in the claims.

30 In the drawings:—

Figure 1 is a perspective view of a shoe of conventional form, and illustrating the application of a fastening device constructed in accordance with the invention,

35 Fig. 2 is a transversely sectional view taken substantially upon line 2—2 of Fig. 1.

Fig. 3 is a top plan view of one of the plates constituting a part of the supporting body, and

40 Fig. 4 is a sectional view illustrating the manner in which the body is fastened to the shoe and showing the means by which the plates constituting the body are secured together.

45 Referring now more particularly to the drawings, the body consists of a plurality of plates 5 pivoted together at their ends as at 6. These plates may be formed of thin metal and by pivoting the same together in 50 the manner shown, it is obvious that they may adapt themselves to the shape of the foot. One end of each of the plates is depressed a distance equal to the thickness of the next adjacent plate, as indicated at 7, 55 and this depressed portion is adapted to receive and support the said end of the next

adjacent plate, rivets or pivot pins 8 being employed to secure the said ends together. The end plate of the central supporting body is bent at its free extremity as at 9 so as to 60 provide a hook adapted to engage in an eyelet in the shoe at the base of the tongue of the latter.

Each of the plates 5 is provided at its longitudinal edges with slots 10, within which 65 the inner ends of the members 11 engage, the hooks at the outer ends of the members 11 being indicated at 12.

In practice, the central supporting body consisting of the plates 5 is positioned between the adjacent front edges of the shoe, and the hook member 9 is engaged within a suitable eyelet adjacent the base of the tongue of the shoe. The supporting body rests upon the instep, and the hooks 12 which 70 project laterally from the various plates are engaged within the eyelets in which the lacing 75 for the shoe are usually threaded. When the device has thus been applied to the shoe, it is obvious that the same will be 80 held properly fitted upon the foot, and the hook members will securely hold the shoe uppers against becoming loose upon the foot. The material of which the device is 85 constructed may be of cheap or expensive metal, and if desired, the various plates may be engraved or may be studded with precious stones.

The foregoing description and the drawings have reference to what may be considered the preferred, or approved form of 90 my invention. It is to be understood that I may make such changes in the construction and arrangement and combination of parts, materials, dimensions, etc., as may 95 prove expedient and fall within the scope of the appended claims.

Having thus fully described my invention, what I claim as new and desire to secure by Letters Patent, is:—

1. In a securing device of the class described, a central supporting body, and hook members carried by said body and projecting laterally beyond the same.

2. In a securing device of the class described, a central supporting body, a fastening member on said body for securing the latter to a base, and hook members carried by said body and projecting laterally beyond the same.

3. In a securing device of the class described, a central supporting body, means for

105

100

110

securing the same to a base, and hook members arranged in spaced relation upon said body and projecting laterally therefrom.

4. In a securing device of the class described, a central flexible supporting body, means for securing the said body to a base, and hook members hinged upon said body and projecting laterally in spaced relation therefrom.

10 5. In a securing device of the class described, a central supporting body comprising a plurality of links connected together end to end, and hook members on each link projecting laterally therefrom.

15 6. In a securing device of the class described, a central supporting body comprising a plurality of plates pivoted together end to end, a hook at the free end of one of the links of said body, each link being provided

adjacent its longitudinal edges with slots, 20 and hook members secured at their inner ends in said slots.

7. In a securing device of the class described, a central supporting body comprising a plurality of plates, one end of each plate being depressed a distance equal to the thickness of the next adjacent plate and being adapted to support the end of the said next adjacent plate, pivots connecting the said ends of said plates, and hooks projecting laterally from the said plates. 25

In testimony whereof I affix my signature in presence of two witnesses.

THEODORE BUTLER
